UNITED STATES PATENT OFFICE.

HERBERT S. MILLS, OF OAK PARK, ILLINOIS.

COIN-CHUTE FOR VENDING-MACHINES.

1,029,209.

Specification of Letters Patent. Patented June 11, 1912.

Application filed February 8, 1912. Serial No. 676,314.

To all whom it may concern:

Be it known that I, HERBERT S. MILLS, a citizen of the United States, residing at Oak Park, in the county of Cook and State of Illinois, have invented a new and useful Improvement in Coin-Chutes for Vending-Machines, of which the following is a specification.

The object of my invention is to equip the coin-chute of a vending machine with means for effectively arresting and directing out of the chute any spurious disk of magnetic metal that may be used in an attempt to operate the machine fraudulently.

My improvement is designed, more particularly, for use in a coin-chute of a vending machine the delivery mechanism of which is adapted to be rendered operative by the attainment therein of a predetermined position by a coin of proper denomination run through the chute; and my purpose, in that connection, is to prevent a disk of steel, iron or other magnetic metal, from being used for rendering that mechanism so operative, 25 by arresting it in its course through the chute and causing it to fall out of the same.

In the accompanying drawing, Figure 1 shows a coin-chute by a view in side elevation equipped with my improvement; Fig. 30 2 shows the same but with the face-plate of the chute removed to show details of my improved means, and Figs. 3 and 4 are sections respectively on the lines 3 and 4, Fig. 2.

A coin-chute 5, of the construction shown 35 or of any other desired construction, as provided in any vending-machine, inclines downwardly from a coin-insertion slot 6 provided in a suitable part of the machine-case, represented at 7; and it leads at its 40 distal-end to discharge therefrom a coin, introduced at the slot, into a position in the machine to render operative the delivery-mechanism thereof, so that if a mere steel or iron disk of proper dimensions be used, 45 its discharge from the chute will introduce it into position for rendering the machine thus operative. To obviate this I provide the chute, between its ends, and preferably nearest its inner end as shown, with a vertical slot 8, the bottom of which affords a 50 discard-opening 8' leading by preference into the bottom of the casing of the machine. A magnet 9, of the preferred horseshoe type of permanent magnet represented, is fastened to a side of the metal chute in position to extend its poles nearly to the rear

end of the slot 8. In the upper end of that slot is pivoted, to hang more or less loosely therein in the path through the chute, a stop shown as a finger 10.

The magnetic field within the chute, with the small magnet 9 secured to the outer side of the chute-wall, is weak, in the sense of being inadequately powerful to overcome the momentum of a disk of magnetic metal 65 rolling through the chute and clearing the opening 8' the same as would a suitable coin, which is non-magnetic and the momentum of which would overcome the slight resistance of the stop 10 and clear it. The extent of 70 obstruction opposed by the pivotal stop to a coin or disk of steel, or the like, is enough, however, to maintain either momentarily in the magnetic field, but, of course, without magnetic influence on the coin. If, though, 75 such a disk be used, the retarding of its progress by the stop in the magnetic field exposes it sufficiently to the influence of the magnet to maintain it long enough at the opening 8' to cause it to discharge there-through by gravity and thus dislodge itself from obstructing, for subsequent operation of the machine by a proper coin, the passage through the chute, besides frustrating the fraudulent purpose with the dislodged disk.

I am aware that it is old to provide a magnet in position to arrest a disk in its course through the coin-chute of a vending machine for preventing it from exerting the function 90 of a proper coin in the latter; and it may also be old to interpose a yielding stop in the coin-path. It is new, however, to provide in co-operative relation to each other and to a spurious coin-discard opening in 95 the bottom of such a chute, a magnetic field too weak to alone overcome the momentum of and halt a disk of magnetic metal rolling in the chute through said field and a yielding stop, to adapt the latter to perform the 100 function of sufficiently overcoming the momentum of the disk to expose it to the weak magnetic field adequately for the arresting influence thereof on the spurious token to cause it to drop by gravity out of the chute 105 through the opening.

What I claim as new and desire to secure by Letters Patent is—

1. In combination, a coin-chute provided between its ends with a bottom discard-opening, a magnet having its field at one end of said opening and insufficiently power-

ful to alone overcome the momentum of and
halt a disk of magnetic metal rolling in the
chute through said field, and a yielding stop
extending into the coin-path through the
chute at the opposite, advance end of said
opening and operating, in conjunction with
said magnet, to sufficiently retard the pro-
gress of such disk through said chute as to
cause it to discharge through said discard-
opening, said stop presenting a degree of
resistance insufficient to prevent the pas-
sage of a coin through said chute and past
said opening.

2. In combination, a coin-chute provided
between its ends with a bottom discard-
opening, a magnet having its field at one end
of said opening and insufficiently powerful
to alone overcome the momentum of and
halt a disk of magnetic metal rolling in the
chute through said field, and a pivotal stop-
finger depending into the coin-path through
the chute at the opposite, advance end of
said opening and operating, in conjunction
with said magnet, to sufficiently retard the
progress of such disk through said chute as
to cause it to discharge through said dis-
card-opening, said stop-finger presenting a

degree of resistance insufficient to prevent
the passage of a coin through said chute and
past said opening.

30

3. In combination, a metal coin-chute pro-
vided between its ends with a slot forming
a discard-opening in the chute-bottom, a
magnet secured to the outer surface of a wall
of the chute to bring its field at one end of
said opening and exert its magnetic action
through said chute-wall, said field being in-
sufficiently powerful to alone overcome the
momentum of and halt a disk of magnetic
metal rolling therethrough in the chute, and
a pivotal stop-finger depending into the
coin-path through the chute at the opposite,
advance end of said opening and operating,
in conjunction with said magnet, to suffi-
ciently retard the progress of such disk
through said chute as to cause it to dis-
charge through said discard-opening, said
stop-finger presenting a degree of resistance
insufficient to prevent the passage of a coin
through said chute and past said opening.
